UNITED STATES PATENT OFFICE.

MARTIN JUREK, OF DALLAS, TEXAS.

DESIGN FOR A SHAVING-CABINET.

59,967.

Specification for Design.

Patented Dec. 13, 1921.

Application filed April 15, 1921. Serial No. 461,691. Term of patent 7 years.

To all whom it may concern:

Be it known that I, MARTIN JUREK, a citizen of Czechoslovakia, residing at Dallas, in the county of Dallas and State of Texas, have invented a new, original, and ornamental Design for a Shaving-Cabinet, of which the following is a specification, reference being had to the accompanying drawing, forming part thereof.

The figure is a view in perspective of a shaving cabinet, showing my new design.

I claim:

The ornamental design for a shaving cabinet as shown.

MARTIN JUREK.
